SCREW-HOLDING DRIVERS

Arthur Blakey Hallam, Leeds, England, assignor to Chas. F. Thackray Limited, Leeds, England, a British company

Application July 20, 1953, Serial No. 369,179

Claims priority, application Great Britain July 28, 1952

7 Claims. (Cl. 145—52)

This invention relates to screw drivers of the type incorporating screw-holding means which grip the screw and hold it in the required position whilst it is driven wholly or partly into position.

Various devices have been constructed and incorporated into screw drivers for holding the screw during the operation of screwing into position. In some cases spring claws or slotted tips are furnished at the end of the screw driver with a driver tip located behind them and relative movement is provided between the two parts. In one known construction a screw driver has a rod axially mounted within a sleeve carrying the tool handle and a slotted hollow tip into which the screw can readily be inserted for its head to lie within the tip in line with the driver tip. The latter is in the form of a spring-loaded plunger in the end of the rod and the latter is moved axially by means of a screw head which requires to be rotated clockwise or anti-clockwise into the handle to cause the rod to project or withdraw. Such rod approaches the screw, the driver tip enters the screw head slot and then continued movement of the rod causes the latter to slide over the driver tip until its end bears against the screw head and holds it firmly in the screw-holding tip. The disadvantage with this arrangement is that the action of screwing the rod into or out of position is rather lengthy, and is a two-handed operation and in many cases quick action is desirable.

According to the present invention there is provided a screw driver incorporating a screw-holding device and a screw head pressure applicator mounted to allow relative axial movement between the two parts, a driver tip to rotate a held screw when the tool handle is turned and a pivoted lever for causing the relative axial movement between the two parts for applying pressure on the head of the screw. The construction may be such that a screw is held in a hollow of a holding tip on the screw driver sleeve with a rod in the sleeve carrying a driver tip and axially movable by means of a pivoted lever carried by the tool handle, rear part of the driver sleeve, or a member housed therein and linked to the rod.

The screw driver may include a pivoted lever for the quick operation and release of a pressure applicator rod carrying a spring loaded driver tip, said lever being resilient adjacent its fulcrum and between it and the pivot of a link extending between the lever and the said rod whereby said pivot can pass over the dead centre between the fulcrum and link pivot on the rod. The arrangement may be such that adjustment can be allowed between the lever fulcrum and the pressure applying end of the driver tip carrying rod. The screw-holding tip may be cupped or recessed on its outer face or otherwise shaped and positioned to enable said tip to be located on the head of a partly driven-in screw and the driver tip then to be projected through the holding tip

2

to drive a round or flat headed screw fully home into position.

Referring now to the accompanying drawing in which several embodiments of the invention are shown:

5 Fig. 1 is a sectional side elevation of one form of improved screw-holding driver;

Fig. 2 is a front elevation of a modified form of screw-holding driver;

Fig. 3 is a sectional side view of the operating end of a screw-holding driver;

10 Fig. 4 is a sectional side elevation of a further modified form of screw-holding driver; and

Fig. 5 is a sectional side elevation of the operating end of a screw-holding driver with a lever catch.

15 In a particular embodiment of this invention shown in Fig. 1 there is provided a screw driver incorporating a screw-holding device and means for applying pressure on the screw head. The screw driver includes a sleeve 2 to which the tool handle 3 is secured at one end and

20 a screw-holding tip 4 is furnished at the other end. The latter is hollow with an opening 5 in one side and a slot 6 which enables the head and stem or neck of the screw to be inserted and held axially in relation to the screw driver sleeve. In the latter is mounted a pressure-applying rod 7 carrying a driver tip 8 projecting from its outer end and spring loaded at 9 in the end of the rod. When the rod is in position the driver tip projects into the hollow screw-holding tip and is clear of the head of a screw. The rod is prevented from rotating

30 by having fins or other projections 10 which slide in slots 11 in the tool sleeve, although the rod may be of square or other section in a complementary bore. To give axial movement to the rod a lever 12 is mounted in the handle 3 by means of a fulcrum pin or screw 13

35 passing through the handle and the lever is enlarged at 14, substantially in U-shaped formation, i. e. the lever end is flattened with a transverse hole 15 through it and a slit 16 leading thereto so that there is resilience between the two legs of a U. The fulcrum is on one

40 side of this slit and a pivot pin 17 passes through the other part and on this pivot is a link 18 which is pivoted at 19 at its other end to the end of the rod. Thus as the lever is forced inwardly towards the handle the link pivot swings about the fulcrum and as it approaches

45 dead centre the U-shaped part of the lever closes slightly and then beyond the dead centre eases outwardly slightly thus retaining the rod rigidly in its position against rearward movement. This operating movement of the

50 rod forces its end face 20 towards the screw head and during this movement the driver tip enters the screw head and the rod moves over the tip and against the screw head due to the spring loading. As it is desirable to allow for adjustment in the distance between the lever fulcrum and the pressure end of the rod the link

55 is attached to a screwed part 21 inserted into the end of the rod and furnished with a lock nut 22.

60 In a modification shown in Figs. 2 and 3, the adjustment for the pressure applying rod carrying the driver tip is provided between the lever fulcrum and the tool handle. A mounting pin 23 is carried by the fulcrum 13 of the lever which does not engage the tool handle. The end of this pin 23 enters a screw-threaded plug 24 fitted axially into the end of the tool handle. The plug can rotate about the pin and the two are engaged, say by a circlip 25 in the plug engaging an annular groove in the pin, so that withdrawal of the plug lengthens the distance between the fulcrum and the pressure tip 20 of the rod and as the plug is moved inwardly, the distance will be shortened. This adjustment enables the rod to be set in relation to a screw head according to the size of the latter.

In Fig. 4 is shown a modified form of screw-holding driver more suitable for mass-production methods. In this the screw-driver sleeve 2 is extended sufficiently to house part of the operating means. The end of this sleeve is screw-threaded externally to receive an adjusting cap 26 in which is rotatably anchored the lever mounting pin 23. Thus as the cap is screwed onto or off the sleeve the aforesaid adjustment is again achieved. A slot 27 is formed in the driver sleeve to accommodate the U-shaped part 14 of the lever and allow movement of the link 18. Furthermore, a projecting pin 28 on the driver rod slides in this slot to prevent rotation of the rod. This slot in the sleeve registers with the slot in the handle 29 which may be moulded onto the sleeve, or a preformed handle is secured thereon in any convenient manner.

In the aforesaid constructions the pivot connecting the link of the U-shaped part of the lever is adapted to move beyond dead centre when the lever is closed down, thus holding the screw-driver in its operative position. In some cases it may be desirable to have a lever which can be retained in its closed position and have a quick release action. A suitable arrangement is shown in Fig. 5 wherein when the lever is closed down the said pivotal connection 17 has not reached the centre and thus the lever would swing back if not held. To hold the lever in position a spring-loaded pivoted catch 30 is furnished with its head 31 engaging over the tip of the lever to hold the latter down in position. To release the lever the person gripping the screw-driver can simply push the lever head in the direction of the arrow against the spring loading whereupon the lever will spring up to its open position. On releasing the catch it will return to its normal position and when the lever is pressed down again it will force the catch back slightly and the catch head will spring back to hold the lever down.

It will readily be understood the screw-holding driver may be modified to suit requirements, e. g., instead of a simple gripping handle, which can be fluted or otherwise shaped to facilitate the grip, the screw-holding driver may be part of an ordinary brace handle similar to a carpenter's brace. Moreover, with either a simple or brace handle any known form of ratchet driving mechanism may be incorporated according to known practice.

What I claim is:

1. A screw driver incorporating a shank, means for rotating the shank, a screw holding tip on the end of

said shank to receive the head of the screw, a pressure applicator rod axially slidably but non-rotatably mounted in said shank for its outer end to engage and clamp the screw head in the shank tip, an axially displaceable spring loaded driver tip in said clamping end of the rod to engage the screw head and rotate with the rod, a pivoted lever connected by a link to the rod to give it axial movement and apply pressure on the screw head, said lever being connected through its fulcrum to a mounting element, an adjustable thrust member engaging the said element to make the pressure applicator rod initially adjustable in relation to a screw head, and means providing resilience of the operating lever adjacent its fulcrum between the latter and the pivot of its link connection to the rod to ensure a firm grip on a screw head and allow for slight variations in screw heads.

2. A screw driver according to claim 1, characterised in that the lever resilience and mounting is such that its pivotal connection to the link can pass over the dead centre between the lever fulcrum and link pivot on the rod to maintain pressure on a screw head through the rod.

3. A screw driver according to claim 1, characterised in that the lever is substantially U-shaped at its fulcrum end to provide resilience between its fulcrum and its connection to the pressure applicator rod.

4. A screw driver according to claim 1, wherein the thrust member is carried by a handle on the tool shank.

5. A screw driver according to claim 1, wherein the thrust member is carried by the tool shank.

6. A screw driver according to claim 1, characterised in that said pivoted lever is mounted and connected to the pressure applicator rod so as to spring back from its closed position, and a releasable catch for retaining the lever closed.

7. A screw driver according to claim 1, characterised in that said pivoted lever is mounted and connected to the pressure applicator rod so as to spring back from its closed position, and a spring loaded quick release catch for retaining the lever closed.
